UNITED STATES PATENT OFFICE.

LOUIS B. PENDLETON, OF ST. LOUIS, MISSOURI.

CHECK-BOOK.

Specification of Letters Patent.

Patented Nov. 24, 1914.

1,118,042.

Application filed November 8, 1913. Serial No. 799,893.

To all whom it may concern:

Be it known that I, LOUIS B. PENDLETON, a citizen of the United States, residing at the city of St. Louis, State of Missouri, have invented a certain new and useful Improvement in Check-Books, of which the following is a full, clear, and exact description, such as will enable others skilled in the art to which it appertains to make and use the same, reference being had to the accompanying drawings, forming part of this specification, in which—

Figure 1 is a plan view of a check book of my improved construction, the same being open to show the face of a check and its respective stub or record sheet and also showing one of the stubs or record sheets folded and turned over onto the inside of the front cover of the book. Fig. 2 is a face view of one of the stubs or record sheets, the same being detached from the book. Fig. 3 is an edge view of the stub or record sheet with dotted lines showing the manner in which the same is folded after being filled out. Fig. 4 is an enlarged detail sectional view taken approximately on the line 4—4 of Fig. 1, and showing a retaining device for the checks and record sheets.

30 My invention relates to a new and useful pocket check book, the principal object of my invention being to provide a comparatively simple, inexpensive check book wherein the greater portion of the face of the check, or that portion which is filled out, and the face of the record sheet or stub are arranged immediately adjacent to each other so that the user can quickly and conveniently fill out the stub or record sheet and 35 the check without the inconvenience of turning over a stub or leaf of the book or without shifting the writing operation from one side of the book to the other.

40 A further object of my invention is to provide a record sheet or stub with spaces or columns which, when filled out, and the record sheet is folded and turned over onto the inside cover of the book, will occupy positions in direct alinement with spaces 45 which are adapted to receive data relating to deposits made by the user of the book, thus greatly simplifying the keeping of records relating to the user's bank balance and the various issued checks.

50 55 A further object of my invention is to

provide means whereby the free edges at the outer ends of the checks and record slips are temporarily held in convenient position on the back cover of the book until they are successively removed by the user. 60

With the above and other objects in view my invention consists in certain novel features of construction and arrangement of parts, hereinafter more fully described and 65 claimed.

70 My improved check book, as shown, comprises a series of checks 10 of suitable size and shape, the same being bound in any suitable manner between covers 11 and 12 and the main body portions of said checks being readily detachable from the bound edges along perforated or weakened lines such as 13.

75 Inscribed or printed on the face of each check is a series of lines adapted to receive the usual date or memoranda, as for instance, the "Check Number", the "Date", the "Name of the Payee", the amount for which the check is drawn, and the maker's name.

80 Bound into the book and overlying a portion of the face of each check is a series of record sheets or stubs, such as 14, each stub being approximately equal in length to the length of the check, and approximately half 85 the width thereof. Each record sheet is arranged so that it overlies the upper portion of the face of the adjacent check. The upper portion of the record sheet is cut away so as to form an approximately rectangular opening 15 which exposes that portion of the adjacent check 10 on which the check number, and date spaces appear. Immediately below the lower edge of this opening 15 on the face of the record sheet is a 90 date line or space 16, and immediately below this is a space or line 17, which is adapted to receive the name of the payee and in front of which is printed suitable data such as "In Favor Of".

95 100 Appearing on the left hand portion of the record sheet and near the top thereof is a line or space 18 adapted to receive the check number, and immediately below this line or space is a series of lines 19 adapted to receive memoranda relating to the check or to the transaction of which the check is issued. Extending across the body of the record sheet in alinement with the edge thereof at the right hand end of the opening 15 110

is a creased line 20 which permits the right hand portion of the record sheet to be readily folded over onto the central portion thereof when said record sheet has been filled out and is folded over onto the front cover of the book.

Printed on the face of the record sheet near the upper right hand cover thereof, are lines which form vertical columns 21 and 22, the same being headed "Dollars" and "Cents", and directly to the left of these columns and in alignment with the horizontally arranged spaces thereof appears the data "Balance Brought Forward", "Amount of this Check" and a balance.

Formed in the right hand ends of all of the record sheets and checks are short inwardly extending slots 23, the same being in direct alignment with the edges of the record sheets below the openings 15 therein. The distance from the right hand end of the opening 15 in each record sheet to the right hand edge of said sheet is approximately equal to the length of said opening so that when the right hand portion of said record sheet is folded over on the creased line 20, the upper half of the right hand portion of said record sheet will overlie the opening 15 and the slot or notch 23 in the end of said record sheet can be engaged with the edge of said sheet at the left hand end of said opening, thereby locking the right hand portion of said sheet in its folded position. This arrangement is clearly shown at the left hand of Fig. 1 where the record sheet has been folded and then turned over onto the inner face of the front cover of the book. The notches 23 not only provide means for holding the right hand ends of the record sheets in their folded positions, but are adapted to receive the shank 24 of a stud 25, the same being seated in and projecting upwardly from the back cover 12. Such construction provides for the retaining of the unused checks and record sheets in proper and convenient position upon the back cover 12.

Inscribed or printed on the reverse side of the record sheet immediately below the opening 15 is a series of lines which form vertical columns 26, the same being divided by horizontally disposed lines 27 and these columns are located so that when the right hand portion of the record sheet is folded over onto the central portion of said sheet, and then turned over onto the front cover of the book, said columns will appear in direct vertical alignment with the columns 21 and 22. The spaces within the columns 26 are adapted to receive the amounts of deposits which may be made by the user of the book, and the lowermost spaces in said columns are preceded by the printed words "Balance Carried Forward."

The reverse side of the left hand portion

of each record sheet is provided with spaces 28 adapted to receive data relating to the deposits entered in the columns 26.

The use of my improved book is as follows: The maker of the check writes the number of the check in the proper spaces, once upon the upper left hand portion of the record sheet and once upon the upper central portion of the check, which portion is exposed through the opening 15. The date is then written upon the proper line on the face of the check immediately below the number, and this date is also written in the proper space 16 on the central portion of the record sheet. The name of the payee is now written in the space 17 on the record sheet and said name is also written on the proper space on the face of the check immediately below the lower edge of the record sheet. The amount for which the check is issued is now written in the proper spaces on the face of the check and said amount is also written in the columns 21 and 22 opposite the data "Amount of this Check." The user notes the amount in the columns 26 of the folded over record sheet opposite the notation "Balance Carried Forward" and inserts the figures representing this amount in the columns 21 and 22 opposite the notation "Balance Brought Forward." The amount for which the check is being issued is now subtracted from the amount of the balance brought forward and the remainder is inserted in the spaces beneath the columns 21 and 22 opposite the notation "Balance." Upon signing the check the user detaches the right hand end of the record sheet from the retaining stud 25 and folds said record sheet upon the creased line 20, thus positioning the right hand edge of said record sheet immediately over that portion of the record sheet at the left hand end of the opening 15. The edge of the paper of which the record sheet is formed at the left hand side of the opening 15 is now engaged in the notch 23 of said record sheet thereby retaining the folded portion in proper position on the central portion of said sheet and the same in its folded condition is now turned over onto the inside of the front cover 11 of the book. This exposes the upper portion of the reverse side of the folded end through the opening 15 and the columns 21 and 22 are brought into alignment with the columns 26. As deposits are made the amounts thereof are entered in the columns 26 and when a succeeding check is to be issued, the total amount of the deposits plus the balance appearing in the lowermost spaces of the folded over portion of the record sheet are entered in the spaces opposite the notation "Balance Carried Forward," and this amount is also entered in the upper spaces of the columns 21 and 22 opposite the notation "Balance Brought Forward."

Forward." Thus the user has all the necessary data relative to the amount of his bank account and by properly filling in the different data on the faces of the record sheets and checks, it is a comparatively easy matter to keep a complete record of all checks and the transactions for which the same were issued.

By providing a record sheet which overlies a portion of the face of the check, it is a comparatively easy matter for the user to properly fill out the record sheet at the same time the check is being made out and the user is not inconvenienced by having to shift the writing operations from one side of the book to the other or by having to turn or raise the record sheet during the writing of the necessary data thereon, and upon the check.

20 I do not desire to be understood as limiting myself to the precise arrangement of columns or the headings and notations on the record sheet and check as the same may be varied to suit different requirements.

25 I claim:

1. In a check book the combination with a series of superposed blank checks of a series of record sheets arranged between the checks so that each record sheet overlies a portion 30 of the face of the check, which record sheets are approximately equal in length to the length of the checks, and of a width less than the width of the check a portion of each record sheet being cut away so as 35 to expose a portion of the reverse side of said record sheet when the same is folded upon a predetermined line and to expose a portion of the face of said record sheet when the same is folded over onto the front cover 40 of the book, and the face of each record sheet being printed to form spaces in which may be written data corresponding to the data written upon the face of the corresponding check.

45 2. In a check book, a series of superposed checks, a corresponding series of record sheets arranged with one sheet overlying each check, said record sheets being approximately equal in length to the length of the 50 checks and half the width thereof, each sheet overlying the upper half of the face of the check, the upper central portion of each record sheet being cut away so as to expose a portion of the corresponding check, 55 all of the sheets being printed to form spaces adapted to receive data corresponding to the data written on the checks, and each record sheet being transversely creased at a predetermined point so as to permit a 60 portion of the sheet to be readily folded.

3. In a check book, the combination with

a blank check, of a record sheet which is approximately equal in length to the length of the check and having a width less than the width of the check, which record sheet 65 overlies the upper portion of the blank check, said record sheet being suitably printed to form spaces adapted to receive data corresponding to the data written on the check, a portion of the record sheet being cut away to expose a portion of the face of the corresponding check, and a portion of the rear side of the record sheet being printed to form spaces which are adapted to receive certain data, and which last mentioned spaces are in alinement with certain of the spaces on the face of the record sheet when a portion of the latter is folded on a predetermined transverse line.

4. In a check book, a record sheet adapted 80 to overlie a portion of the face of a check, which record sheet is approximately equal in length to the length of the check and having a width less than the width of the check, a portion of which record sheet is cut away 85 to form an opening which exposes a portion of the face of the corresponding check, said record sheet being transversely creased at one end of the opening so as to be readily folded at a predetermined point and both sides of which record sheet are printed to form spaces adapted to receive data corresponding to the data written on the face of the corresponding check and certain of the spaces on the face of the record sheet being 95 positioned so that they will aline with certain spaces on the rear face of said sheet when the same is folded on the creased line.

5. In a check book, a blank check, a record sheet having a length approximately equal 100 to the length of the check and having a width less than the width of the check, which record sheet overlies a portion of said check and positioned so that the record sheet and the blank check can be filled out without disturbing the position of either, and said blank check and record sheet being provided with spaces located so that when said spaces are properly filled out, the name of the payee on the check will be immediately 110 adjacent to the name of the payee on the record sheet, and the spaces containing the numerical notations on said record sheet will be above and adjacent to the numerical notations on the check.

In testimony whereof I hereunto affix my signature in the presence of two witnesses, this 5th day of November, 1913.

LOUIS B. PENDLETON.
